UNITED STATES PATENT OFFICE.

CARL BERGLAND, OF EAST ORANGE, NEW JERSEY, ASSIGNOR TO LAUTER COMPANY, OF NEWARK, NEW JERSEY, A CORPORATION OF NEW JERSEY.

DESIGN FOR A PLAYER-PIANO LEVER.

42,989.

Specification for Design.

Patented Sept. 10, 1912.

Application filed May 2, 1912. Serial No. 694,737. Term of patent 3½ years.

To all whom it may concern:

Be it known that I, CARL BERGLAND, a citizen of the United States, residing at East Orange, in the county of Essex and State of New Jersey, have invented a new, original, and ornamental Design for a Player-Piano Lever, of which the following is a specification, reference being had to the accompanying drawing, forming part thereof.

The figure is a perspective view, showing my new design.

I claim:

The ornamental design for a player piano lever, as shown.

CARL BERGLAND.

Witnesses:

WILLIAM CHESTER WEBB,
S. R. CAIRNS.
